[57] ABSTRACT

[21] Appl. No.: 126,244

A unit for placement within a fireplace of a house, the device serving to humidify the air of a room, the device comprising a housing forming a reservoir containing water, the water being heated by the smoke carrying thermo heat passed the housing so to heat the water into steam, the smoke after circulating passed the housing then curling back into the fireplace due to a specifically shaped baffle formed along a forward side of the housing.

INVENTOR
WILLIAM C. GERLACH

FIREPLACE HUMIDIFIER AND SMOKE RETURN

This invention relates generally to room humidifiers.

A principal object of the present invention is to provide an improved room humidifier for a house which is fitted into a fireplace so to utilize the heat therefrom to vaporize a quantity of water for humidifying purposes.

Another object of the present invention is to provide a fireplace humidifier which includes a hollow housing that serves as a reservoir for a quantity of water, the water being heated into steam by the heat from the fireplace.

Yet another object of the present invention is to provide a fireplace humidifier having a specially configurated baffle thereof so to permit circulation of smoke from the fireplace there around, the smoke carrying thermo heat for heating the water.

Other objects of the present invention are to provide a fireplace humidifier and smoke return which is simple in design, inexpensive to manufacture, rugged in construction, easy to use and efficient in operation.

These and other objects will be readily evident upon a study of the following specification and accompanying drawing wherein:

FIG. 1 is a top front perspective view of the present invention, and

FIG. 2 is a cross-sectional view taken on line 2—2 of FIG. 1.

FIG. 3 is a similar view thereof shown mounted in a fireplace shown in side cross section.

Referring now to the drawing in detail, the reference numeral 10 represents a fireplace humidifier and smoke return according to the present invention wherein there is a hollow housing 11, the hollow housing serving as a reservoir within which a quantity of

water is placed.

The humidifier is made from formed sheet metal and includes an open trough 12 along a forward edge thereof which is adjacent a rear side of a front baffle 13.

The baffle 13 is specially configurated and has a lower portion thereof which extends downwardly lower than the humidifier housing 11, the baffle serving to direct the movement of smoke from the fireplace passed the humidifier housing so that thermo heat can be transferred from the smoke directly to the same. Thereafter the smoke is caused to curl back into the fireplace due to the specifically shaped baffle.

In operative use, it is now evident that the water is thermally heated so to turn to steam which then vaporizes into the air of the room, thus humidifying the room air.

What I now claim is:

1. In a fireplace humidifier and smoke return, the combination of a housing, said housing being made of formed sheet metal, said housing forming an enclosure that serves as a reservoir for containing water, said housing being provided with a longitudinally extending trough along a forward upper edge thereof, said trough communicating with the interior of said housing and providing a means for evaporation of said water from said reservoir, and a specifically configurated baffle being formed along a front side of said housing, said baffle having a portion thereof extending higher than said trough adjacent a rear side thereof, and a lower end of said baffle extending downwardly a greater distance than the lower side of said housing, said baffle serving to direct the movement of smoke from said fireplace, said baffle being of double arcuate configuration.
